UNITED STATES PATENT OFFICE.

CHARLES E. McDOWELL, OF NEW YORK, N. Y., ASSIGNOR OF ONE-HALF TO
HENRY W. GENNERICII, OF SAME PLACE.

DESIGN FOR A CASING FOR VENDING-MACHINES.

SPECIFICATION forming part of Design No. 25,649, dated June 16, 1896.

Application filed March 4, 1896. Serial No. 581,860. Term of patent 7 years.

To all whom it may concern:

Be it known that I, CHARLES E. McDOWELL, a citizen of the United States, residing at New York, in the county of New York and State 5 of New York, have invented a certain new and useful Design for a Casing for Vending-Machines; and I do hereby declare the following to be a full, clear, and exact description of the invention, such as will enable others skilled 10 in the art to which it appertains to make and use the same, reference being had to the accompanying drawing, and to letters of reference marked thereon, which form a part of this specification.

15 My design has for its object to furnish an original and, from a structural point of view, attractive and graceful casing for vending-machines, the design varying in details to suit the object I have in view.

20 The leading features in this design are as follows:

In the accompanying drawing, A indicates a polygonal pyramidal-shaped roof, whose sides are concave and overlaid with shingles.

25 Surmounting this roof is a miniature dome-shaped top C. The middle part B is, as shown

in the drawing, a decahedron. The sides of this storage part B alternate with each other as glass and mirrors, mirrors, as B' and B², and decorated pieces of glass, such as B³ and B⁴. 30 The lower part or pedestal E of this casing corresponds in number of sides to the middle part B in its architectural design. The sides of the pedestal are grooved or fluted to correspond with the design given to the two upper 35 parts.

The combined features as here described produce thus a casing for vending-machines, of a graceful architectural exterior, attractive in appearance, and 40

What I consequently claim as a novel design for this class of articles is—

The design for a casing for vending-machines, as herein shown and described.

In testimony that I claim the foregoing I 45 have hereunto set my hand this 21st day of February, 1896.

CHARLES E. McDOWELL.
